EARTHING DEVICE FOR ELECTRIC OIL-BREAK SWITCHES.

1,326,028.

Specification of Letters Patent. Patented Dec. 23, 1919.

Application filed December 7, 1918. Serial No. 265,778.

To all whom it may concern:

Be it known that we, FRANK COATES and JAMES MIRREY, subjects of the King of England, and residing at Cleadon, Durham, England, and East Boldon, Durham, England, respectively, have invented certain new and useful Improvements in Earthing Devices for Electric Oil-Break Switches, of which the following is a specification.

10 This invention relates to earthing devices for electric oil-break switches and is primarily concerned with the earthing of the conductors of an insulating switch to insure safety in handling such conductors when uncovered by the removal of the oil tank.

In good modern practice on high voltage systems it is usual to provide isolating or interlocking arrangements for the purpose of insuring that the conductors are disconnected before the oil tank is lowered and in some cases the removal of the tank is positively prevented by some interlocking devices until such isolation has been accomplished. Such arrangements under certain 25 conditions are insufficient owing to the possibility of leakage of current through the isolating device due say to the presence of dirty oil. Again the conductors of the switch may be accidentally charged with a 30 dangerous voltage through the inductive effect of a current in a neighboring conductor. Or the conductor may retain a charge due to its own electrostatic capacity. Thus there may be danger in handling the conductors 35 of a switch although such switch may be isolated so far as the mere opening of switch members is concerned. The object of the present invention is to prevent such a contingency from arising and to make absolutely sure that the conductors are safe to 40 handle.

An electric oil-break switch according to this invention is provided with one or more earthing members so arranged and disposed 45 that the conductors or contacts within the oil tank must be earthed before they are rendered accessible by the removal of the tank.

In one construction the earthing member is in the form of a pivoted arm or blade 50 within the oil tank operated by mechanism outside the tank and connected to the pivoted arm say by a plunger passing through the cover of the tank. The operating mechanism which may be of any suitable kind

is so interlocked with the gear for lowering 55 or otherwise removing the tank that such gear cannot be operated to remove the tank until the conductors within the tank have first been earthed, through the movement 60 of the pivoted arm.

In another construction also according to this invention the earthing member within the tank is so arranged that it is moved automatically so as to earth the conductors during the removal of the tank and before 65 such conductors are rendered accessible. This may be accomplished by the provision of two arms or levers pivoted on a spindle within the oil tank such arms being acted upon by a spring coiled around the spindle 70 so that they tend to move downward and to make connection with the two conductors which form the contacts of the switch. Preferably each arm is provided with a spring contact blade carrying a contact with 75 rounded edges so that as the arm moves downward the contact on the spring blade makes easy but sure contact with the conductor. In such a construction arrangements are made whereby the earthing members are held inoperative when the oil tank 80 is in its normal closed or "on" position. For instance each of the pivoted arms may be provided with a projecting portion or lug which when the tank is raised into its 85 "on" position, is engaged by a bracket or the like fixed on the inside wall of the tank so that the arm is raised against the action of its spring. During the removal of the tank and before the switch contacts are rendered accessible by such removal, the withdrawal of the brackets or the like releases the pivoted arms which consequently move 90 under the action of the spring and make earthing contact with the switch conductors. 95 The replacement of the oil tank into its "on" position automatically withdraws the earthing members from their connection with the switch conductors and resets them in their normal position ready to operate again in 100 the manner described.

A similar resetting arrangement may be provided in the construction first mentioned in which the movement of the earthing member is brought about by mechanism 105 from outside the tank.

In the accompanying drawings,
Figure 1 is a sectional elevation of an oil-

break isolating switch provided with one construction of earthing device according to this invention.

Fig. 2 is a side elevation of the mechanism for operating the earthing device.

Figs. 3 and 4 are respectively a plan and an elevation of a portion of another form of earthing device also according to this invention, and

10 Fig. 5 is a sectional elevation of the upper portion of an isolating switch having two earthing members similar in construction to that shown in Figs. 3 and 4.

15 All the figures are purely diagrammatic and various parts of the switch gear not essential to the present invention are omitted.

With reference first to Figs. 1 and 2 the oil tank A is shown provided with raising and lowering gear operated from a shaft B 20 having a crank handle B'. The isolating switch C contained in the tank is shown conventionally as operated by a rod C' and as is well known in oil-break isolating switches the mechanism for opening the switch C may be interlocked with the shaft B so that the tank A cannot be lowered until the switch C has been opened. With this interlocking mechanism however the present invention is not concerned. Two conductors D D' are shown passing through the fixed cover of the tank to the switch C and one of these D' is provided with a contact E which may be connected to earth e. g. to the cover of the tank when a pivoted 30 contact arm F is moved downward by means of a rod F'. Any convenient means may be provided for operating this rod F' but in the construction shown in Figs. 1 and 2 it is moved by means of a pin engaging with 35 the slotted crank G on a spindle G' furnished with a handle G'.

To insure that the earthing switch F must be moved into connection with the contact E thus earthing the conductor D', before 40 the tank A can be lowered, interlocking mechanism is provided between the earthing switch and the tank-lowering gear. In the construction illustrated this is shown by way of example as an engagement between 45 the upper portion of the rod F' and a pulley-like boss H on the shaft B. The member H has a hole or recess in its periphery into which the end of the rod F' passes when 50 it is in its raised position and thus until the rod F' is withdrawn by partially rotating the shaft G' the shaft B cannot be rotated to lower the oil tank A. The movement of 55 the shaft G' necessary to withdraw the rod F' from the member H causes the earthing switch F to move down and make connection with the contact E.

60 The arrangement may be such that the contact between the members F and E cannot be broken that is to say the conductor D' must remain earthed until the tank is

again raised. Obviously in the example illustrated this might be brought about by proportioning suitably the diameters of the pulleys B² controlling the vertical movement of the tank A. For if less than one revolution of the shaft B is necessary for the complete lowering of the tank then the arrangement may be such that the rod F' cannot be returned into the hole or recess in the member H until the shaft B has been 70 rotated back into the position shown in the drawings.

75 In the construction shown in Figs. 3 and 4 the earthing switch instead of being operated independently before the lowering of the tank is moved automatically into position to earth the conductors during the removal of the tank and before the conductors are rendered accessible. In this construction the earthing switch F² is in the 80 form of an arm pivoted at J in a bracket K attached say to the cover of the tank A'. Around the spindle J is coiled a spring J' one end of which bears against a portion of the arm F² and tends to force that arm down into the position shown in chain lines in Fig. 4. When in that position the spring contact F³ on the earthing switch makes rubbing connection with one of the switch conductors D² and earths that member. 85 When the oil tank A' is in its raised position a bracket A² fixed to the tank A' engages with a lug F⁴ forming part of the switch arm F² and raises that member against the action of the spring J' into the 90 position shown in full lines in Figs. 3 and 4.

95 The initial lowering movement of the tank A' withdraws the bracket A² and allows the earthing switch F² to move down under the action of the spring J' and earths the conductor D² before the tank has been lowered sufficiently to render the conductors in the tank accessible.

100 The switch arm F² is shown provided with a projection or lug F⁵ which forms a limiting stop for the downward movement of the arm F² by engaging with the web of the bracket K. When the tank A' is replaced the bracket A² again engages with the end of the lug F⁴ and lifts the arm F² up into 105 its normal position against the action of the spring J'.

110 The construction shown in Fig. 5 is similar in form and operation to that described with reference to Figs. 3 and 4 except that 115 two earthing switches F⁶ and F⁷ are provided one for each of the conductors D³ and D⁴. The switch arms F⁶ and F⁷ are mounted on a bracket K' on the tank cover A³ and are spring operated as previously described 120 the arms being retained in their "off" position when the tank is raised by brackets A⁴ and A⁵ one of the brackets preferably being on one side of the tank and the other on the opposite side.

It is understood that the constructions shown are purely by way of example and that any suitable forms of earthing switches may be employed and may be interlocked with the tank lowering gear or operated by the raising and lowering of the tank in any appropriate way.

Although the invention has been described with particular reference to an isolating switch it may be applied to any electric oil-break switch having one or more conductors which it is desirable to earth before the oil tank is removed.

Oil is referred to in the specification as the insulating liquid but obviously other known liquids suitable for the purpose may be employed.

What we claim as our invention and desire to secure by Letters Patent is:—

- 20 1. The combination of an electric oil-break switch, a tank therefor, a movable earthing member within the tank, and means for moving the earthing member into contact with a conductor within the tank, 25 to earth such conductor before it is rendered accessible by the removal of the tank.
2. The combination of an electric oil-break switch, a tank therefor, an earthing member mounted so that it can be moved 30 into contact with a conductor within the tank, mechanism outside the tank for moving the earthing member, gear for lowering or otherwise removing the tank and means for interlocking the mechanism for 35 moving the earthing member with the lowering gear so that the tank cannot be removed until the conductor is earthed.

3. The combination of an electric oil-break switch, a tank therefor, a movable

earthing member within the tank, and means 40 for automatically moving the earthing member into contact with a conductor within the tank to earth such conductor during the removal of the tank and before such conductor is rendered accessible.

4. The combination of an electric oil-break switch, a tank therefor, and a spring-operated earthing member within the tank arranged so that it is moved automatically 50 into contact with a conductor within the tank during the removal of the tank and before such conductor is rendered accessible.

5. The combination of an electric oil-break switch, a tank therefor, a spring-operated earthing member within the tank ar- 55 ranged so that it is moved automatically into contact with a conductor within the tank during the removal of the tank and before such conductor is rendered accessible and means whereby the earthing member is 60 restored to its normal position when the tank is replaced.

6. The combination of an electric oil-break switch, a tank therefor, a cover to said tank, an earthing switch arm pivotally 65 mounted on the inside of the cover, a spring tending to cause the earthing switch arm to move into contact with one of the oil-break switch conductors in the tank and a projecting member on one of the side walls of the 70 tank, such projecting member engaging with the earthing switch arm and preventing its movement under the action of the spring until the tank is withdrawn.

In testimony whereof we have signed our 75 names to this specification.

FRANK COATES.
JAMES MIRREY.
